(57) **CLAIM**

The ornamental design for a beverage bottle, as shown and described.

DESCRIPTION

FIG. 1 is a front view of a beverage bottle, showing my new design;

FIG. 2 is a back view thereof;

FIG. 3 is a right side view thereof;

FIG. 4 is a left side view thereof;

FIG. 5 is a top view thereof;

FIG. 6 is a front top perspective view thereof;

FIG. 7 is a back top perspective view thereof;

FIG. 8 is a bottom view thereof;

FIG. 9 is a front bottom perspective view thereof; and,

FIG. 10 is a back bottom perspective view thereof.

The broken lines in the drawing view depict portions of the beverage bottle that form no part of the claimed design.
